UNITED STATES PATENT OFFICE.

WILHELM GRAAFF, OF BERLIN, GERMANY.

ICE-MAKING MACHINE.

1,082,944.

Specification of Letters Patent.

Patented Dec. 30, 1913.

Application filed September 26, 1911. Serial No. 651,290.

To all whom it may concern:

Be it known that I, WILHELM GRAAFF, merchant, a subject of the German Emperor, and, residing at 17 Linkstrasse, Berlin, 5 W. G., in the Kingdom of Prussia, Germany, have invented certain new and useful Improvements in Ice-Making Machines, of which the following is a specification:

The present invention relates to ice-making machines and, in particular, to such in which the refrigerating medium is expelled from a solution in the one of two communicating, permanently closed and evacuated vessels and then condensed in the other of 15 these vessels and subsequently again allowed to evaporate, whereupon the vapors produced are again absorbed in the first vessel. The vessel first mentioned, in which the refrigerating medium is expelled from a 20 solution or mixture and in which it is again absorbed shall hereinafter be referred to as the absorber and the second vessel, in which the cold medium is condensed and again reevaporated shall be referred to as 25 the refrigerator.

A machine of the hereinbefore mentioned type has, for instance, been described in the United States Patent 958,683. The present invention relates to the special arrangement 30 of the refrigerator in machines of the type mentioned. In the machines hitherto known the refrigerator was either a smooth cylinder or a body composed of tubes or lenticular elements for the purpose of increasing its surface. These refrigerators have the disadvantage, that their construction is rather complicated and that, owing to the numerous joints, it is difficult to prevent leakage. Furthermore the vapor 35 space and the liquid space in these refrigerators, even if made as small as possible, are still too large, so that the condensation of the vapors proceeds very slowly, and the evaporation in the absorber might therefore be carried too far. These disadvantages are avoided in the present invention by the refrigerator being made approximately bell-shaped, as for instance, by providing an outer cylinder surrounding an 40 inner cylinder which is open at one end. By varying the diameter of this inner cylinder it is possible to make the volume of the refrigerator of any desired size so as to obtain the most favorable ratio between the vapor space and the surface 45 of the refrigerator to be cooled, so that

the vapors passing from the absorber to the refrigerator will be rapidly condensed. The described arrangement of the refrigerator will furthermore reduce the liquid space, the liquid preferably only reaching up to the communicating pipe between the refrigerator and the absorber, which allows of a sufficiently large quantity of distillate in the refrigerator. In consequence thereof 60 all vapor passing over into the refrigerator will be condensed into a liquid form, but all surplus liquid produced in the refrigerator will flow through the hollow shaft back into the absorber where it will be again evaporated. By such means the mixture contained in the absorber can never be evaporated beyond a given degree of concentration and an overheating and consequent decomposition of the chemicals contained in the absorber is impossible, and the efficiency of 65 the machine will therefore not be impaired. Further advantages of such bell shaped refrigerators consist in that it is of simple design and can be easily and surely kept 70 tight, and that both refrigerator and absorber may be made of the same length, whereby the manufacture of the machine is greatly simplified.

The drawing illustrates a constructional 75 form of the present invention in diagram and part section.

In this drawing *a* is the vessel serving as distiller and absorber, *b* the vessel serving as the condenser and refrigerator. The pipe *c* 90 forms a means of communication between the two vessels. This pipe, which passes through the absorber *a*, is provided within the latter with perforations, so that the vapors can pass freely from *a* to *b* or from 95 *b* to *a*. The ends of pipe *c* projecting from the absorber rest in suitable bearings *d*, so that both vessels can be rotated by means of a crank *e* or any other suitable device. Within the vessel *a* are arranged plates *f*, 100 which are preferably made of a dish-like shape and perforated. These plates serve to promote the conduction of the heat and the agitating of the absorption liquid, besides increasing the evaporating or absorbing surfaces respectively and preventing the absorbing medium being carried over into the condenser.

In the free head wall of the vessel *b* is arranged a second, preferably cylindrical 110 vessel *g* so as to have a close joint therewith, and the cavity of the vessel *b* is thereby con-

siderably reduced. The ratio between the dimensions of vessels *g* and *b* is so chosen, that only such liquid space is left in vessel *b*, as is required for the quantity of distillate necessary for the production of ice. If the machine is therefore heated a little too long, so that more liquid is evaporated than will be required for producing the ice, all surplus liquid distillate will flow through the hollow shaft *c* from vessel *b* back into vessel *a*. It is therefore impossible for the absorption medium in vessel *a* to be overheated. As furthermore the vapor space of the refrigerator is correspondingly reduced, the vapor passing over from *a* will more quickly come into contact with the cool walls of the same, so that the distillation is considerably accelerated.

In consequence of the hereinbefore described arrangement of the refrigerator the cooling surface of the same is on the one hand considerably increased, so that during the distillation process the cooling may be effected simultaneously from inside in the cavity *k* and from outside, for instance by means of sprinkler pipes *h* and *i*, and on the other hand ice may be produced during the freezing process both within the cavity *k* and on the outer surface of the refrigerator, for instance in a hood of suitable shape placed over the same.

The invention is not limited to the above-mentioned bell shaped form of the refrigerator, as any other suitable form may be used to the same advantage.

I claim

1. In an ice-making machine the combination of a vessel serving as an absorber

with a vessel serving as a refrigerator, both vessels being in axial alinement, and a cooling arrangement for said refrigerator; said absorber being provided with a hollow axle which extends along its whole length and opens centrally into one end of said refrigerator, said hollow axle having a plurality of radial perforations within the absorber, and a plurality of diaphragms in the absorber, said diaphragms having each a plurality of perforations.

2. An ice making machine having an absorber and a condenser in axial alinement, said absorber comprising a cylinder with a plurality of centrally open diaphragms, an axially situated hollow shaft rigidly connected to the cylinder and projecting at both ends thereof, said shaft having radial perforations within the cylinder; external bearings for said shaft wherein it is mounted to revolve; said condenser being rigidly mounted at one end of said shaft and comprising an outer and an inner vessel forming a closed chamber between them, said chamber communicating with the interior of the absorber through said shaft and its perforations; said inner vessel being open at one end; sprinkling means for the inside of said inner vessel and the outside of said outer vessel, heating means for the absorber and revolving means for said shaft, whereby the absorber and the condenser may be simultaneously rotated.
